(57) **CLAIM**

The ornamental design for a handheld respiratory airway device, as shown and described.

DESCRIPTION

FIG. 1 is a right side perspective view of a handheld respiratory airway device, made according to the new design; FIG. 2 is a left side perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; and, FIG. 8 is a bottom plan view thereof.

The broken line showing in FIG. 4 forms no part of the claimed design.
